BY

ATTORNEYS.

UNITED STATES PATENT OFFICE.

MAX SCHEUER, OF NEW YORK, N. Y.

PURSE OR POCKET-BOOK.

SPECIFICATION forming part of Letters Patent No. 488,742, dated December 27, 1892.

Application filed October 10, 1892. Serial No. 448,278. (No model.)

To all whom it may concern:

Be it known that I, MAX SCHEUER, of New York city, New York, have invented an Improvement in Purses and Pocket-Books, of which the following is a specification.

This invention relates to an improvement in pocket books, purses and similar articles and more particularly to a novel manner of assembling and connecting the various parts 10 that constitute the lid or cover of the purse or pocket book.

The invention consists in the various features of improvement more fully pointed out in the claims.

15 In the accompanying drawings: Figure 1 is a perspective view of a purse provided with my improvement. Fig. 2 a top view of the lid with plate *c*, removed. Fig. 3 a face view of bottom plate *d*. Fig. 4 a face view of top plate *c*, and Fig. 5 a cross section through the purse.

The letter *a*, represents the body of a pocket book, satchel or similar article and *b*, is the U-shaped frame of the lid or cover hinged to the frame *a'*, of the pocket book, by pivots *a*². The frame *b*, is grooved (Fig. 5) and receives a top plate *c*, and a bottom plate *d*, the latter being provided if desired with a suitable edging *d'*. Both plates *c*, *d*, are slipped freely 30 into the U-shaped frame *b*, from the rear open end thereof. Between the plates *c*, *d*, there is confined a tongue *a*³, that constitutes an integral part of the material from which the body of the purse is formed and which thus 35 serves as the connecting link between the body of the purse and the body of the cover.

In order to secure the plates *c*, *d*, as well as

the tongue *a*³, to the frame *b*, I provide the top plate *c*, at its rear end with a pair of prongs *c'*. These prongs enter perforations 40 *a*⁴, of the pocket book *a*, directly back of the bottom plate *d*. The prongs are then upset (Fig. 5) upon the inner side of the bottom plate. In this way, it will be seen, both the bottom plate and top plate are secured to the 45 body of the pocket book and are together with tongue *a*³, prevented from slipping out of the frame *b*. Thus all the parts constituting the lid are assembled and connected in a neat, simple and substantial manner. 50

What I claim is:

1. The combination of a purse or pocket book with a pivoted frame and with a top plate received thereby and having prongs that project through perforations in the purse 55 body, substantially as specified.

2. The combination of a purse or pocket book with a pivoted frame and with a top plate and bottom plate received thereby, the top plate having prongs that project through 60 perforations in the purse body, back of the bottom plate, substantially as specified.

3. The combination of a purse or pocket book having a tongue *a*³, with a grooved pivoted frame and with a top plate and bottom 65 plate received thereby and placed above and below the tongue, the top plate being provided with prongs passing through perforations of the purse body and upset against the bottom plate, substantially as specified.

MAX SCHEUER.
